UNITED STATES PATENT OFFICE.

ALBEN E. LUNDELL, OF NEW YORK, N. Y., ASSIGNOR TO WESTERN ELECTRIC COMPANY, OF NEW YORK, N. Y., A CORPORATION OF ILLINOIS.

SUBSTATION SENDER-CIRCUIT.

1,148,912.

Specification of Letters Patent.

Patented Aug. 3, 1915.

Application filed February 27, 1915. Serial No. 114052.

To all whom it may concern:

Be it known that I, ALBEN E. LUNDELL, a citizen of the United States, residing at New York, in the county of Bronx and State of New York, have invented certain new and useful Improvements in Substation Sender-Circuits, of which the following is a full, clear, concise, and exact description.

This invention relates to telephone exchange systems, and more particularly to circuits for use with substation sending devices for automatic telephone exchange systems.

Heretofore in automatic telephone systems, in which the calling subscriber operates a calling device or impulse sending mechanism to control the operation of selecting apparatus, the making and breaking of the line control circuit by the sending mechanism caused irritating noises to be set up in the calling subscriber's receiver, which noises were disagreeable and sometimes dangerous.

The object of the present invention is the provision of a substation circuit for use with a calling device or impulse sending mechanism and in which all possibility of noise in the receiver due to the making and breaking of the control circuit by the sending mechanism is avoided.

The invention will be particularly described in its embodiment in the substation circuit illustrated in the accompanying drawing.

Referring to the drawing, 10 designates the usual ringer in series with a condenser 11 in the normal circuit of the line conductors 1 and 2. The telephone transmitter 12 and the primary winding of an induction coil 13 are included in a normally open bridge of the line conductors, and are arranged to be brought into circuit upon the removal of the telephone receiver 14 from its switch-hook 15, said receiver and the secondary winding of the induction coil 13 being also brought into circuit upon the removal of the receiver.

Associated with the substation circuit is a calling device or impulse sending mechanism 16 having a wheel 17 rotatable about the axis 18, and provided with teeth 19. A bell crank lever 20 pivoted at 21 is located in operative relation to the wheel 17, one arm of which is engaged by the teeth on the wheel 17, the other arm engaging a contact

arm 22 which engages with a contact 23 located in the line conductor 2. Two conductors 24 and 25 are brought out from the induction coil leads, as shown, and terminate in the contact 26 and switch contact 27 respectively. An arm 28 is fastened to the shaft 18 and movable with the wheel 17. This contact 26 and switch contact 27 constitute an off-normal switch, and the closing of this switch, when the calling device moves from normal, places a shunt around the receiver 14, which shunt is maintained until after the required number of impulses is sent, and the calling device returns to normal.

The operation is as follows: Upon the removal of the receiver 14 from the switch-hook 15, the signaling circuit is closed from battery through the right winding of the signal relay 29, line conductor 1, primary of the induction coil 13, switch-hook 15, transmitter 12, impulse contacts 22, 23, line conductor 2, left winding of relay 29, back to battery. The subscriber now operates the calling device 16 by means of a dial, to send the impulses necessary to make connection with the subscriber wanted. As a preliminary to sending the impulses, the wheel 17, together with the arm 28, is moved in the direction of the arrow the required distance, after which it is returned to normal by the action of a spring, (not shown). Upon leaving the normal position the arm 28 allows the off-normal switch to close, placing a shunt circuit 24, 26, 27, 25 about the receiver 14.

As at this time there is steady current from battery flowing through the primary of the induction coil, the placing of the shunt about the receiver causes no change in the flow of current through the primary, and hence no disagreeable click is produced in the receiver. In its return to normal the teeth 19 contacting with the bell crank 20 make and break the signaling circuit at the contacts 23, 23, energizing and deenergizing the relay 29 the required number of times. The making and breaking of the signaling circuit produces current changes in the primary of the induction coil 13, which produce current changes in the secondary. The receiver, however, being shunted, is not affected by the current changes in the secondary, after the sending of the impulses and upon the return of the wheel 17 to normal the off-normal switch

105
110

contacts 26, 27 are opened, but as at this time there is a steady flow of current from battery through the signaling circuit, there is no effect produced in the receiver.

5. What is claimed is:

1. A substation circuit for automatic telephone systems having in combination a calling device, a signaling circuit including the primary of an induction coil, a receiver in series with the secondary of said induction coil, a switchhook and means controlled thereby for completing said signaling circuit, and a shunt about said receiver, and contacts in said shunt operated when the calling device leaves its normal position, whereby the shunt circuit is completed.
2. In a substation circuit for automatic telephone systems, the combination of a line circuit, a receiver, an induction coil, means for placing said receiver and induction coil in inductive relation to said line circuit, a calling device, means controlled thereby for sending impulses to said line circuit, and further means controlled by said calling device when moved from its normal position for placing a shunt about said receiver, whereby a change of potential in the receiver is prevented during the sending out of impulses.
- 30 3. In a substation circuit for automatic

telephone systems, the combination of a line circuit comprising two branches, a receiver, an induction coil, means for placing the primary of said induction coil in series with the line branches and the receiver in inductive relation to said primary, a calling device for sending impulses over said line branches in series, a shunt circuit about said receiver, and means controlled by said calling device for opening said shunt after the sending of the impulses. 35

4. In a substation circuit for automatic telephone systems, the combination of a line circuit comprising two branches, an induction coil, a receiver connected in series with the secondary winding of said induction coil, means for connecting the primary of said induction coil in series with said line branches, a calling device having means for sending impulses over said line branches in 45 series, and further means for placing a shunt about said receiver when the calling device is moved from normal.

In witness whereof, I hereunto subscribe my name this 24th day of February A. D., 1915. 55

ALBEN E. LUNDELL.
